MOTOR-DRIVEN VENTILATING UNIT
MOUNTING

Karl Johan Arvid Nellvén and Karl Erik Hjelm,
Stockholm, Sweden, assignors, by mesne assignments,
to Aktiebolaget Enköpings Verkstader, Enköping, Sweden, a corporation of Sweden

Application November 18, 1947, Serial No. 786,658
In Sweden November 27, 1946

4 Claims. (Cl. 98—43)

1

Our invention relates to motor-driven ventilating units, and is especially concerned with mounting such ventilating units at an opening or duct in a wall on an enclosure.

One of the objects of our invention is to provide an improved mounting for a motor-driven fan or ventilating unit which is constructed in such manner that the ventilating unit can be readily detached from and secured in position on the mounting structure to facilitate inspection and cleaning of the ventilating unit.

Another object of our invention is to provide an improved mounting for a motor-driven fan or ventilating unit in which the electrical connection for the fan motor is automatically made and broken when the ventilating unit is positioned on the mounting structure and detached therefrom.

A further object is to provide a mounting for motor-driven fans or ventilators which is constructed in such manner that it can be positioned and secured in place at openings or ducts of different cross-sectional area in a range normally encountered in building practice.

The novel features which we believe to be characteristic of our invention are set forth with particularity in the claims. The invention itself, however, both as to organization and method, together with further objects and advantages thereof, will be better understood by reference to the following description taken in connection with the accompanying drawings in which:

Fig. 1 is a view taken at line 1—1 of Fig. 3, partly in section and partly in elevation, of a ventilating unit embodying the invention;

Fig. 2 is a fragmentary sectional view, taken at line 2—2 of Fig. 3, to illustrate parts of the ventilating unit more clearly;

Fig. 3 is a fragmentary vertical sectional view, taken at line 3—3 of Fig. 1;

Fig. 4 is a front elevation of parts of the ventilating unit shown in Figs. 1 to 3;

Fig. 5 is a sectional view taken at line 5—5 of Fig. 4;

Fig. 6 is a top plan view of a detail of the parts shown in Figs. 4 and 5;

Fig. 7 is a front elevation of another arrangement of parts like those shown in Figs. 4 and 5;

Fig. 8 is a vertical sectional view taken at line 8—8 of Fig. 7;

Fig. 9 is a fragmentary sectional view corresponding to Fig. 5 illustrating a modification of the invention;

Fig. 10 is a fragmentary front elevation of the

2

details shown in Fig. 9 and which corresponds to the view illustrated in Fig. 4;

Fig. 11 is a view similar to Fig. 4 illustrating another modification of the invention; and

Fig. 12 is a vertical sectional view taken at line 12—12 of Fig. 11.

Referring to Figs. 1 to 3, we have shown our invention in connection with a room ventilating unit having an annular housing 10 formed by an inner cylindrical sleeve or wall member 11, an annular member 12 which is L-shaped in section and forms the front and outer side walls and a rear plate 14. The front end of the cylindrical sleeve 11 telescopically fits over a flange or collar 15 of the annular member 12 and these parts, together with the rear plate 14, are held in assembled relation by hollow sleeves 16, the front ends thereof being grooved at 17 to receive the peripheral edges of apertures formed in the front of the annular member 12 and the reduced rear ends thereof being externally threaded to receive tightening nuts 18 which bear against the rear plate 14.

The cylindrical sleeve 11 defines an air passageway within which is centrally disposed a fan 19 fixed to a shaft of an electric motor 20 having a major portion thereof extending outside the air passageway from the rear of the housing 10. The motor 20 is resiliently carried by the housing 10 by a number of spaced apart reverse bent members 21 having the inner ends thereof fixed at 22 to the cylindrical sleeve 11 and the outer ends thereof, which are desirably covered at 21a with rubber or like material, rigidly fixed to the casing of the motor 20 by a clamp 23.

Within the housing 10 is disposed control mechanism for controlling the motor 20 and the position of a movable shutter 24 arranged at the front of the housing and overlying one end of the air passageway. As best shown in Fig. 3, such control mechanism includes a switch 25 removably secured in any suitable manner to the rear plate 14 and from which current is supplied through leads 26 and 27 to the motor 20. The switch 25 is connected in a circuit including leads 28

45 and 29 fixed to a conventional connector or connecting plug 30 whose pins 31 are received in the openings of a contact socket or receptacle 32 to which current is supplied by leads 33 and 34, as seen in Fig. 2.

In order to mount the connecting plug 30 in the housing 10 the rear plate 14 is provided with an opening to the peripheral edges of which is fixed the flanged open end 35 of a hollow cap 36, the closed end of which is apertured to receive the

55

connecting plug 30. The portion of the plug body remote from the pins 31 firmly rests against the inner surface of the front of the casing 10 and an intermediate recessed portion thereof is notched to receive an ear or tab 37 which is formed at the apertured closed end of the cap 36, thereby locking the connector 30 in position and preventing turning movement thereof so as to definitely position the spaced apart connector pins 31.

The switch 25 is provided with an actuating member 38 to which is fixed the upper end of a control rod 39 for controlling the operation of the motor 20. The control rod extends downwardly through the housing 10, the lower part being accessible at the exterior of the housing, as seen in Fig. 1. The control rod 39 may be arranged to simultaneously control the motor 20 and adjust the position of the shutter 24. In order to simplify the drawing, the mechanism operatively associating the control rod 39 and the shutter 24 has not been illustrated. However, such mechanism may be of any suitable type and like that described in an application of Karl J. Walkborg, Serial No. 601,444, filed June 25, 1945, the disclosure of which may be considered as being incorporated in this application.

In accordance with one phase of our invention we provide an adjustable mounting unit 40 for a ventilator like that just described for rigidly and snugly mounting the ventilator in position in different size openings or ducts in walls of existing building structures or dwellings. As shown in Fig. 1 the mounting unit 40 comprises a hollow rectangular frame 41 provided with top and bottom positioning and locking members 42 and 43 which are received by openings 44 and 45, respectively, formed in an L-shaped annular rim 46 fixed to an opening or duct 47 of a wall 48. Rims or facing plates of annular form and like the rim 46 are usually employed in openings or ducts in existing building structures, and this is especially true in kitchens in which such facing plates, not originally intended for use in mounting a ventilator, are provided with diametrically opposed top and bottom openings for some purpose, such as, for example, to position a rotatable damper.

The frame 41 is adapted to overlie the opening or duct against which it is positioned and bear against the front face of the rim 46. The positioning and locking members 42 and 43 are adjustable to and from the front face of the rim and the top member 42 is also vertically adjustable to accommodate the ventilator associated with the frame 41 to openings or ducts which vary in size over the range usually encountered in walls of existing building structures. The bottom positioning and locking member 43 is in the form of a pin which depends downwardly from the underside of a plate or bridge member 49 intermediate the ends thereof, as best shown in Figs. 4 and 5.

The bridge member 49 spans the gap between a pair of spaced apart tabs 50 extending rearwardly from the bottom horizontal arms of the frame 41, the bridge member being removably secured to the tabs, as by cap screws 51, for example. As best seen in Fig. 6, the bridge member is formed with elongated or oval shaped openings 52 through which the cap screws 51 pass, so that the bridge member and pin 43 at the underside thereof can be adjusted to the desired position in the mouth of the opening or duct 47 and fix the pin in vertical alignment with the bottom opening 45 in the rim 46, thereby enabling the

pin 43 to be accurately positioned with respect to the bottom opening 45.

The top positioning and locking member 42 is in the form of an elongated cap screw which is vertically adjustable in a block 53. The block 53 in turn is secured by cap screws 54 to the frame 41, two vertical rows of opening 55 being provided on the frame for the screws so that the block can be attached to the frame at different vertical positions. For each particular size opening or duct to which the frame 41 is to be attached, the block 53 is positioned at the most convenient height on the frame by the screws 54 and the final adjustment is made by the cap screw 42 itself to lock the frame rigidly in position. The cap screws 54 also serve to adjust the position of the block 53 to and from the front face of the rim 46 so that the top locking and positioning member 42 can be readily aligned with the top opening 44 in the rim or facing plate.

When using the ventilator mounting of the invention, the rectangular frame 41 is first attached to the mouth of an opening or duct 47 by adjusting the cap screws 51 in the bridge member 49 and the cap screws 54 for the block 53 so that the pin 43 and elongated screw 42 are the requisite lateral distance from the frame 41 and in vertical alignment with the rim openings 44 and 45, respectively. In such adjusted position of the pin 43 and locking screw 42, the frame 41 snugly fits against the front face of the rim or facing plate 46. The pin 43 is inserted into the bottom rim opening 45 and the cap screw 42 is then moved vertically upward on the block 53 so that the upper end thereof passes into the top rim opening 44, thereby securely attaching the frame 41 to the mouth of the duct 47.

When the frame unit 40 is secured in position in the duct 47 the ventilator is then mounted thereon. This is accomplished by providing the frame 41 with top and bottom pins 56 which pass through the hollow sleeves 16 and are formed with threaded ends to receive tightening nuts 57 at the front of the housing 10, as best shown in Fig. 1. The receptacle or contact socket 32 previously described is fixed to the frame 41, as indicated at 58 in Fig. 4, the position thereof being such that the pins 31 of the connector 30 will readily move into the contact sleeves or socket apertures 59 when the ventilator is moved rearwardly into position on the pins 56. The housing 10 is suitably notched at the upper part thereof to provide a gap for a conduit 60 through which the leads 33 and 34 are adapted to extend.

In Figs. 7 and 8 we have illustrated an embodiment of the invention in which the mounting unit 40a for the ventilator is adapted to be attached directly to the mouth of an opening or duct of a wall when the building or dwelling is being constructed. In such case the opening or duct is of such size that the mounting unit 40a can be mounted directly in the wall opening, thereby avoiding the necessity of providing a rim or facing plate 46 like that shown in the first described embodiment. As seen in Figs. 7 and 8 each side or leg of the frame 41a is L-shaped in section and is adapted to be secured directly in the mouth of an opening or duct in any suitable manner. Hence, the frame 41a takes the place of the rim 46 and frame 41 in the embodiment illustrated in Fig. 1. In other respects, the frame 41a is like the frame 41 described above in that a receptacle or contact socket 32 is fixed to the upper part thereof to receive the pins 31 of the connector 30 and threaded studs 56 project outwardly therefrom

upon which the ventilator is positioned and carried.

The top locking and positioning member 42 of the mounting unit may take a variety of forms. In Figs. 9 and 10 is shown a modification in which the bent or hooked end 42b of a threaded bolt 61 serves as a top locking and positioning member of a mounting unit 40b. The upper cross arm of the rectangular annular frame 41b is provided with a vertically disposed elongated slot 62 through which the bolt 61 passes, the outer end of which receives a tightening or wing nut 63. By grasping the wing nut 63, the bolt 61 can readily be moved upwardly in the slot 62 to cause the hooked end 42b to pass into the top opening 44 of the rim or facing plate 46. When the hooked end 42b is in its locking position the wing nut 63 can be manually tightened on the bolt 61 to secure the frame 41b rigidly in position in the mouth of the wall opening. Since the slot 62 is more or less centrally positioned at the upper cross arm of the frame 41b, the studs 56 upon which the ventilator is positioned and carried cannot be provided at the center regions shown in Fig. 4 and are desirably removed from such center regions and positioned, for example, at diametrically opposite corners of the frame 41b of the mounting unit.

In certain instances it may be necessary to provide for greater vertical adjustment of the locking and positioning members of the mounting unit than that afforded alone by the top locking and positioning member, as in the first described embodiment and in the modification of Figs. 9 and 10. In such case the bottom locking member may also be arranged so that it is vertically adjustable on the mounting unit. Such a modification is shown in Figs. 11 and 12 which is generally like the embodiment first described. However, in addition to providing a top locking and positioning member 42 vertically adjustable on a block 53 which in turn can be fixed by cap screws 54 to the desired height on the top cross arm of the frame 41, the bottom locking and positioning member 43d is also vertically adjustable.

The bottom locking member 43d is in the form of an elongated cap screw which is vertically movable in a block 64 positioned at the rear face of a plate 65 which projects upwardly from the bottom cross arm of the frame 41 and is fixed thereto at 66. The plate 65 is relatively narrow and formed with two vertical rows of openings 67 adapted to receive cap screws 68 threadedly secured to the block 64. By providing the openings 67 in the plate 65 it is possible to adjust the bottom locking and positioning member 43d vertically, which, together with the vertical adjustment effected by the top locking and positioning member 42d, provides an extreme-flexible mounting unit for ventilators of the type described.

By adjustment of the cap screws 68 on the block 64 the latter is moved laterally to and from the rear side of the frame 41 to facilitate bringing the locking member 43d in vertical alignment with the bottom opening 45 of the rim or facing plate 46. By providing a plate 65 which is relatively narrow, the throttling effect of the mounting unit of Figs. 11 and 12 is minimized when it is attached to an existing duct or wall opening whose height is relatively small and a substantial part of the plate 65 projects or extends upwardly above the bottom cross arm of the frame 41.

In view of the foregoing it will now be understood that we have provided an improved mounting for ventilating units which comprises a frame

adapted to be positioned at the mouth of an opening or duct in a wall, the frame including structure, such as the guide pins 56, for example, upon which ventilating unit is bodily supported and detachable therefrom. The ventilating unit is removably secured in position by the tightening nuts 57 which may be grasped by hand for detaching the ventilating unit from the guide pins 56 without use of tools. Even when tools may be required to remove the tightening nuts 57, only an ordinary tool like a pair of pliers, for example, is necessary to effect ready detachment of the ventilating unit which any housewife can use without difficulty when it becomes desirable to clean the ventilating unit from time to time, particularly when such a unit is mounted at an opening of a wall in a kitchen and the parts thereof tend to become coated with grease.

By fixing the connecting plug 30 to a part of the casing 10 and the receptacle or outlet socket 32 to the mounting frame in such a manner that the pins 31 automatically move into and out of engagement with the contact sleeves 59 when the ventilating unit is slidably positioned on the guide pins 56 and removed therefrom, a housewife does not need to tamper with an electrical connection for the fan motor 20 when the unit is removed for cleaning and inspection and again mounted in position.

30 In the embodiment of Figs. 7 and 8 the frame member 41a is formed to be permanently secured in position at the mouth of an opening or duct in a wall at the time the latter is being erected. In such case the frame member may be wedged or locked in position by suitable cement work or by turnable stay members which cooperate with the frame member and are directed backward and bricked up or otherwise locked in position by masonry.

40 In its broader application the mounting unit of the invention is especially useful for installation in openings or ducts of different cross-sectional area in a range normally encountered in building practice, and in such case the frame is provided with elements to secure the same in position at the opening or duct, at least one or both of the elements being adjustable to accommodate and fit the frame to openings of different cross-sectional area between the minimum and maximum size in the range in which it is adapted to be used.

45 Although we have shown and described several embodiments of our improved mounting unit for motor-driven fans or ventilators, we do not wish to be limited to the particular arrangements set forth, and we intend in the following claims to cover all modifications which do not depart from the spirit and scope of our invention.

50 What is claimed is:

60 1. The combination with a ventilating unit comprising a fan and driving motor therefor, of a frame adapted to be mounted at the mouth or opening of a passage or duct in a wall of an enclosure, fastening means at one side of said frame 65 to mount the latter in position at the mouth or duct, said fastening means comprising pins in vertical alignment with one another and adapted to cooperate with diametrically opposed regions in the wall of the duct or passage, at least one of said pins being vertically adjustable with respect to said frame, a mechanical coupling including cooperating first and second means and an electrical connection including cooperating first and second means, the first means of said mechanical coupling and first means of said elec-

trical connection comprising stationary parts disposed at the side of said frame opposite from that of said fastening means, and the second means of said mechanical coupling and second means of said electrical connection comprising stationary parts of said ventilating unit.

2. The combination set forth in claim 1 which further includes an element upon which the lower pin is carried, and means for mounting said element on said frame so that the element is adjustable toward and from said frame.

3. The combination with a ventilating unit comprising a fan and driving motor therefor, of a frame adapted to be mounted at the mouth or opening of a passage or duct in a wall of an enclosure, fastening means at one side of said frame to mount the latter in position at the mouth or duct, said fastening means comprising a pin adapted to cooperate with a wall region of the duct or passage, an element, means for mounting said element in different vertical positions on said frame, said element having an opening threadedly receiving said pin, a mechanical coupling including cooperating first and second means and an electrical connection including cooperating first and second means, the first means of said mechanical coupling and first means of said electrical connection comprising stationary parts disposed at the side of said frame opposite from that of said fastening means, and the second means of said mechanical coupling and second means of said electrical connection comprising stationary parts of said ventilating unit.

4. The combination with a ventilating unit comprising a fan and driving motor therefor, of a frame adapted to be mounted at the mouth or opening of a passage or duct in a wall of an enclosure, fastening means at one side of said frame to mount the latter in position at the mouth or duct, mechanical coupling comprising a plurality

5 of parallel pins in spaced apart relation which are fixed to and project into the enclosure from said frame and a plurality of similarly spaced apart sleeve members adapted to be received by said pins, said ventilating unit comprising a casing in which such sleeve members are mounted, an electrical connection comprising a contact socket or receptacle having openings which is fixed to said frame and a connector or connecting plug carried by said casing, said pins and contact socket or receptacle comprising stationary parts disposed at the side of said frame opposite from that of said fastening means and said sleeve members and connector or connecting plug comprising stationary parts of said ventilator unit, and said connecting plug including elements adapted to fit into the receptacle opening and parallel to said pins when said sleeve members are received by said pins.
